APPARATUS FOR THE CONTROL OF
HIGHWAY CROSSING SIGNALS

Charles W. Bell, Forest Hills, Pa., assignor to
The Union Switch & Signal Company, Swiss-
vale, Pa., a corporation of Pennsylvania

Application December 31, 1937, Serial No. 182,827

11 Claims. (Cl. 246—130)

My invention relates to apparatus for the control of highway crossing signals, and has for an object the provision of novel and improved apparatus controlled by a train approaching the highway crossing for governing the operation of a highway crossing signal capable of displaying three distinctive indications. Other objects and advantages of my invention will appear as the specification progresses.

10 I shall describe two forms of apparatus embodying my invention, and shall then point out the novel features thereof in claims.

For a better understanding of my invention, reference may be had to the accompanying drawing, of which Figs. 1 and 2 are diagrammatic views showing two different forms of apparatus and circuits each embodying my invention.

Similar reference characters refer to similar parts in each of the two views.

20 Referring to Fig. 1, the reference characters 1 and 1a designate the track rails of one track and 21 and 21a designate the track rails of the other track, of a stretch of double-track railway which is intersected at grade by a highway H. 25 Traffic along each track normally moves in the direction indicated by the associated arrow. Highway crossing signals S and S1 are located at the intersection, and preferably face in opposite directions so as to plainly exhibit their indications to highway users approaching the intersection from either direction. The lamps of signal S1 are connected in multiple with the respective lamps of signal S, but the circuits for the lamps of signal S1 are omitted from the drawing for the sake of clearness. As shown in the drawing, the signals S and S1 preferably consist of green lamps G, yellow lamps Y, and red lamps R. The green lamps G are illuminated when no train is approaching the intersection within the limits of 30 the stretch of railway under consideration to display a clear crossing signal to highway users. The yellow lamps Y are illuminated when a train is approaching the intersection to caution highway users that a train is approaching and that a danger or "stop" signal is about to be displayed. The red lamps R are illuminated when the train has reached a predetermined distance from the intersection to indicate "stop" to the highway users. It follows that the three indications of signal S correspond to the green, yellow and red traffic signals usually encountered at street or highway intersections. It will be understood that my invention is not restricted to this one 45 form of highway signal, but other types which are

capable of displaying three distinctive indications may be used if desired.

The track rails 1 and 1a are divided by means of insulated joints 2 to form a track section D—E, extending from the highway in the direction of approaching traffic. A suitable source of current such as track battery 3 is connected across the rails of section D—E at the end farthest away from the highway H, and a neutral track relay TR1 is connected across the rails of this section 10 nearest the highway H. Similarly, track rails 21 and 21a are divided by insulated joints 2 to form a track section J—K, extending from the highway in the direction of approaching traffic, and track battery 3 is connected across one end and relay TR2 across the other end of the rails of section J—K. Located at a predetermined point within track section D—E is a track instrument or track rail contactor C1, which is attached to the rails of section D—E in any suitable manner 20 so as to be actuated by the train independently of the electrical contact between the wheels of the train and the rails of the section. Similarly a track instrument C2 is located within track section J—K and is suitably attached to the rails of section J—K. No particular type of track instrument is required, but any of the well-known mechanical, vibration, mercury, or similar types may be used, as for instance that type covered by United States Letters Patent No. 1,834,077, 30 issued to A. J. Sorensen on December 1, 1931, wherein the resistance is normally low but is increased due to the vibration caused by a passing train; or that type covered by United States Letters Patent No. 2,076,928, issued to H. G. Witmer, on April 13, 1937, wherein a normally closed contact is opened due to the passage of a train. 35

The length of track section D—E is determined by the total length of track that a train will traverse during the period while the caution and stop indications are being displayed by signals S and S1. This distance is dependent upon the maximum speed of trains using the railway and the minimum period desired for the operation of the caution and stop indications. Assuming, for example, a maximum train speed of 90 miles per hour (132 feet per minute) and a minimum caution period of 10 seconds during which the train will travel 1320 feet, and a minimum stop period of 20 seconds during which the train will travel 2640 feet, or a total operating period for the caution and stop indications of 30 seconds, then a train will travel 3960 feet in that period, and under those conditions track section D—E will be 50 55 55 feet in length. Track instrument C1, as

will be shown later, controls the stop indication for each signal S and S₁, and thus track instrument C1 will be located 2640 feet from the highway H. It is understood that these figures are merely illustrative, and that any combination of maximum speed of train and minimum period of display may be used without departing from the scope of my invention. Where in this specification mention is made of other track instruments in other track sections, the location of such track instruments and the lengths of the track sections may be determined as given above.

In addition to the track circuits and track instruments mentioned above, the signal control apparatus consists of a neutral stick relay NR. A stick circuit for relay NR is provided with current from a suitable source such as a battery, not shown, and which circuit passes from terminal B of the current source, through track instruments C2 and C1 in series, front contact 4 and winding 5 of relay NR to the other terminal of the source, designated as C. A pick-up circuit for relay NR is provided with current from terminal B of the current source through front contact 6 of relay TR1, front contact 7 of relay TR2, and winding 5 of relay NR to terminal C.

When no train is approaching the highway within the limits of track sections D—E and J—K, current from each track battery 3 serves to energize the associated track relay TR1 or TR2. A circuit is then completed from terminal B through front contact 10 of relay TR1, front contact 11 of relay TR2, green lamp G of signal S to terminal C, so that the green lamp G is lighted and signal S displays its clear indication. When a train moving toward the right approaches the highway and enters track section D—E, the track circuit is shunted through the wheels and axles of the train, relay TR1 is deenergized, the circuit for green lamp G is broken at front contact 10 of relay TR1, and a circuit is then completed from terminal B through back contact 8 of relay TR1, front contact 9 of relay NR, and yellow lamp Y of signal S to terminal C, so that lamp Y is lighted and signal S displays its caution indication.

The pick-up circuit for relay NR is opened at front contact 6 of relay TR1, but relay NR is retained energized by the previously traced stick circuit. When the train reaches track instrument C1, the instrument is operated to deenergize relay NR, thus opening the circuit for yellow lamp Y at front contact 9 of relay NR, and completing a circuit for red lamp R from terminal B through back contact 8 of relay TR1, back contact 12 of relay NR, lamp R to terminal C, so that red lamp R is lighted and signal S displays its stop indication.

When the train has vacated section D—E, track relay TR1 is reenergized, and front contact 10 of track relay TR1 closes to complete the circuit for green lamp G so that signal S again displays its clear indication; back contact 8 of relay TR1 opens, opening the circuit for red lamp R at that point; and front contact 6 of relay TR1 closes, completing the pick-up circuit for relay NR, re-energizing relay NR.

A train approaching the highway on the other track, in the direction of normal traffic through section J—K, will produce a similar operation of signals S and S₁ by means of the track relay TR2 and track instrument C2.

In the form of invention disclosed in Fig. 2, 22 and 22a designate the rails of a single track railway over which traffic normally moves in

both directions and which is intersected by highway H. That portion adjacent to highway H is divided by insulation joints 2 to form two sections M—N and N—O, which extend in opposite directions from highway H. Track battery 3 is connected across the rails of section M—N at the end farthest away from the highway H, and one magnet 16 of an interlocking relay IR is connected across the rails of this section at the end nearest the highway H. The other magnet 20 of relay IR is connected across one end, and battery 3 is connected across the other end, of the rails of track section N—O. The remainder of the signal control apparatus is similar to that described in Fig. 1 and includes track instruments C1 and C2 located one in each section.

The interlocking relay IR may be of any of the well-known types provided with flagman contacts, and is here shown provided with two front flagman contacts 13 and 14 and a back contact 15 controlled by magnet 16, and with two front flagman contacts 17 and 18 and a back contact 19 controlled by magnet 20. If magnet 16 becomes deenergized before magnet 20 becomes deenergized, front contacts 13 and 14 will open and back contact 15 will close. If magnet 20 is then deenergized before magnet 16 becomes reenergized, back contact 19 does not close, and front contacts 17 and 18 remain closed, so that when magnet 16 becomes reenergized closing contacts 13 and 14, the circuits controlled over contacts 17 and 18 are completed. The operation of the relay is similar for corresponding control of windings 16 and 20 in the reverse order.

When no train is approaching the highway within the limits of track sections M—N and N—O, the front contacts 13 and 17 of the interlocking relay IR close a circuit from terminal B to lamp G of signal S so that signal S displays its clear indication. Signal S, however, is caused to display its caution indication whenever an eastbound train approaches the highway and first enters section M—N, since magnet 16 then becomes deenergized so that its front contact 13 is opened to thereby open the circuit for lamp G, and its back contact 15 is closed to complete an obvious circuit for lamp Y. Front contact 14 of magnet 16 also opens when that magnet becomes deenergized, to thereby open the pick-up circuit for relay NR.

The actuation of track instrument C1 when the eastbound train reaches its location within section M—N results in the release of relay NR, so that front contact 9 of relay NR opens to open the circuit for lamp Y, and back contact 12 of relay NR closes to complete an obvious circuit for lamp R of signal S, with the result that signal S displays its stop indication.

The entrance of the eastbound train on section N—O results in the deenergization of magnet 20, but as was pointed out heretofore, this action of magnet 20 does not affect the opening or closing respectively of the front and back contacts controlled thereby, since the deenergized condition of magnet 16 when magnet 20 becomes deenergized prevents the latter winding from operating its contacts. It is readily apparent that since the contacts of magnet 20 are retained in their original positions, the reenergization of magnet 16 when the eastbound train vacates section M—N results in the opening of the circuit for lamp R and the closing of the circuit for lamp G, so that signal S again displays its clear indication. It is further apparent that with magnet 16 energized, the pick-up circuit for relay NR is completed.

at front contacts 14 and 18 of relay IR, so that relay NR is held energized over its pick-up circuit during the interval that track instrument C2 located within section N-O is actuated by the train. It follows that the actuation of the track instrument located within the track section on the receding side of the intersection does not affect the operation of the highway crossing signals. Then, when the train vacates section N-O and winding 20 becomes reenergized, it can be seen that the apparatus is restored to its normal condition as illustrated in Fig. 2.

The operation of the apparatus of Fig. 2 for a westbound train is substantially similar to the operation just described for an eastbound train, as will readily become apparent from an inspection of Fig. 2, and further detailed explanation is deemed unnecessary.

One advantage of apparatus embodying my invention is the provision of means for controlling a three indication highway crossing signal without the necessity for more than one track circuit on the approach side of the crossing or the necessity for time element devices.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a stretch of railway track intersected by a highway and provided with a single insulated track section extending from said intersection in the direction of approaching traffic, a highway crossing signal capable of displaying three indications and located adjacent to the intersection, a track instrument located within said insulated track section and adapted to be actuated by the mechanical connection of a train with the rails of said section, means effective when no train is approaching the highway for causing the signal to display a first one of said indications, means controlled by a train entering said insulated track section for causing the signal to display a second one of said indications, and means controlled by said train and effective when said train reaches and mechanically operates said track instrument for causing the signal to display a third one of said indications.

2. In combination, a stretch of railway track intersected by a highway and provided with a single insulated track section extending from said intersection in the direction of approaching traffic, a highway crossing signal device capable of displaying a "clear" indication and a "caution" indication as well as a "stop" indication and said signal being located adjacent to the intersection, a mechanically operable track instrument located within said track section, means effective when no train is approaching the intersection for causing the signal to display said "clear" indication, means controlled by a train entering the track section for causing the signal to display said "caution" indication, and means controlled by a train reaching and mechanically operating said track instrument for causing the signal to display said "stop" indication.

3. In combination, a stretch of railway track over which traffic moves in both directions and intersected by a highway, said stretch being divided into two insulated track sections extending in opposite directions from said highway, a highway crossing signal capable of displaying three

indications and located adjacent to the intersection, mechanically operable track instruments located one on each side of said intersection at selected points within said track sections, means effective when both track sections are unoccupied for causing the signal to display a first one of said indications, means effective when either of the track sections is entered by a train approaching the intersection for causing said signal to display a second one of said indications, and means controlled by a train reaching and operating that track instrument within that track section entered for causing the signal to display a third one of said indications.

4. In combination, a stretch of railway track intersected by a highway and provided with a track section extending from said intersection in the direction of approaching traffic, a highway crossing signal capable of displaying three indications and located adjacent to the intersection, a track circuit for the track section including a track relay, a track instrument attached to a rail at a selected point within the track section, a neutral stick relay, a pick-up circuit for the neutral stick relay including a front contact of the track relay, a stick circuit for the neutral stick relay including said track instrument, means including a front contact of the track relay for causing the signal to display a first one of said indications, means including a back contact of the track relay and a front contact of the neutral stick relay for causing the signal to display a second one of said indications, and means including a back contact of the track relay and a back contact of the neutral stick relay for causing the signal to display a third one of said indications.

5. In combination, a stretch of railway track over which traffic moves in both directions and intersected by a highway, said stretch being divided into two track sections extending in opposite directions from the highway, a highway crossing signal located adjacent to said intersection capable of displaying three indications, an interlocking relay, a track circuit for each track section including a magnet of the interlocking relay, track instruments, one located at a selected point within each track section, a neutral stick relay, a pick-up circuit for the neutral stick relay including a front contact of each magnet of the interlocking relay in series, a stick circuit for the neutral stick relay including said track instruments in series, means including a front contact of each magnet of the interlocking relay for causing the signal to display the first one of the said indications, means including back contacts of each magnet of the interlocking relay in multiple and a front contact of the neutral stick relay for causing the signal to display the second one of the said indications, and means including a back contact of each magnet of the interlocking relay in multiple and a back contact of the neutral stick relay for causing the signal to display a third one of said indications.

6. In combination, a stretch of railway track intersected by a highway and provided with a track section extending from said intersection in the direction of approaching traffic, a highway crossing signal capable of displaying three indications and located adjacent to the intersection, a track circuit for the track section, a track instrument located within the track section, means effective when no train is approaching the highway for causing the signal to display a first one of said indications, means controlled by a train approaching the highway and entering the track

- section for causing the signal to display a second one of said indications, means controlled by the train approaching the highway upon reaching said track instrument for causing the signal to display a third one of said indications, and directional means controlled by the approach of the train to the highway for causing the signal to display said first one of said indications when the train recedes from the highway through said track section. 5
7. In combination, a stretch of railway track intersected by a highway and provided with a track section extending from said intersection in the direction of approaching traffic, a highway crossing signal capable of displaying three indications and located adjacent to the intersection, a track circuit for the track section including a track relay, a track instrument attached to a rail at a selected point within the track section, a stick relay, a pick-up circuit for the stick relay including a front contact of the track relay, a stick circuit for the stick relay including said track instrument, means including a front contact of the track relay for causing the signal to display a first one of said indications, means including a back contact of the track relay and a front contact of the neutral stick relay to cause the signal to display a second one of said indications, means including a back contact of the track relay and a back contact of the neutral stick relay for causing the signal to display a third one of said indications, and directional means controlled by a train when moving in the direction to recede from the highway through said track section to render said track circuit and said track instrument ineffective to control the signal. 10
8. In combination, a stretch of railway track intersected by a highway and provided with a track section extending from the intersection in the direction of approaching traffic, a highway crossing signal capable of displaying three indications located at the intersection, a track circuit for said track section including a track relay, a track instrument located at a selected point within said track section, a neutral relay governed by said track instrument, means governed by said track relay for controlling said signal to display a first one of said indications, means governed jointly by said track relay and said neutral relay for controlling said signal to display a second one of said indications, and means governed jointly by said track relay and said neutral relay when controlled by a train actuating said track instrument for controlling said signal to display a third one of said indications. 15
9. In combination, a stretch of railway track intersected by a highway and provided with a track section extending from the intersection in the direction of approaching traffic, a highway crossing signal capable of displaying three indications located at the intersection, a track circuit for said track section including a track re-
- lay, a track instrument located at a selected point within said track section, a neutral relay governed by said track instrument, means including a front contact of said track relay for controlling said signal to display a first one of said indications, means including a back contact of said track relay and a front contact of said neutral relay for controlling said signal to display a second one of said indications, and means including a back contact of said track relay and a back contact of said neutral relay for controlling said signal to display a third one of said indications. 20
10. In combination, a stretch of railway track over which traffic moves in both directions and intersected by a highway, said stretch being divided into two track sections extending in opposite directions from the intersection, a highway crossing signal capable of displaying three indications located at the intersection, a track instrument for each track section located at a selected point within its track section, means effective when both track sections are unoccupied by a train approaching the intersection for controlling the signal to display a first one of said indications, means effective when either one of the track sections is entered by a train approaching the intersection for controlling the signal to display a second one of said indications, means controlled by a train reaching that track instrument located within that track section entered for controlling the signal to display a third one of said indications, and directional means governed by the approach of the train to the intersection for controlling the signal to display said first one of said indications when the train recedes from the intersection through the other one of said track sections. 25
11. In combination, a stretch of railway track intersected by a highway and provided with an insulated section of track extending from the intersection in the direction of approaching traffic, a highway crossing signal capable of displaying three indications and located at such intersection, a track circuit including a track relay for said insulated section of track, a track instrument located at a selected point within said insulated section of track, circuit means governed by said track relay for controlling said signal to display a first one of said indications, and other circuit means governed jointly by said track relay and said track instrument for controlling said signal to display a second or a third one of said indications, said other circuit means being effective to cause said signal to display its second indication provided that a train occupies said insulated section but has not actuated said track instrument and effective to cause said signal to display its third indication provided that a train occupies said insulated section and has actuated said track instrument. 30

CHARLES W. BELL.
